UNITED STATES PATENT OFFICE.

SECONDO FREILINO, OF LEECHBURG, PENNSYLVANIA.

CONVEYER.

Original application filed January 3, 1925, Serial No. 438. Divided and this application filed February 26, 1925. Serial No. 11,815.

My invention relates to an improvement in conveyers, and more particularly to a type of conveyer especially designed to be used with my improved pickling mechanism; and this 5 is a divisional part of my application filed January 3, 1925, Serial No. 438.

This present invention consists of a continuous conveyer including in its combination sprocket-wheels, links, shafts or axles to 10 which are secured the wheels which support and carry the conveyer on tracks, and which shafts or axles form the pivotal connection between the overlapping link ends, which are arranged in spaced-apart pairs at either end 15 of the shafts or axles, the spaces being adapted to receive the teeth of the conveyer sprocket-wheels over and around which the conveyer travels.

In the accompanying drawings:

20 Fig. 1 is a side elevation of a portion of this conveyer;

Fig. 2 is a plan view; and

Fig. 3 is a transverse section.

The conveyer is made up of links 1 and 2. 25 These are spaced apart by spacers 3, and their adjacent ends are pivotally connected by the shafts or axles 4.

The spaces between the links 1 and 2 are 30 adapted to receive the teeth of the sprocket-wheels 1. These sprocket-wheels, of course, are arranged in pairs, at opposite sides of the conveyer, and over and around these sprocket-wheels the conveyer passes. On these shafts or axles 4, the wheels 6 are secured, and these 35 are in position to travel on rails 5 of a track.

Secured over the tops of the links are plates 12. These are in width approximately co-extensive with the length of the links upon 40 which they are supported, so that they turn around the sprocket-wheels with the links. These plates cover the links and shafts or axles, and form a surface upon which the articles which are to be carried by the conveyer are adapted to rest. Stationary guard-rails 7 may be placed at either side to hold 45 the articles on the conveyer.

Rollers 8 may be stationed at intervals beneath the conveyer to support it on its return. The plates 12 being then at the bottom, travel back upon the rollers, as shown 50 in Fig. 1.

In this way, a simple endless conveyer of few parts is provided.

I claim:

55 1. In an apparatus of the character de-

scribed, the combination with a track, of a plurality of shafts, links pivotally mounted in pairs on the opposite ends thereof, spacers interposed between the links of each pair, and wheels loosely mounted on the shafts intermediate the pairs of links in position to travel 60 upon the track.

2. In an apparatus of the character described, the combination with a track, of a plurality of shafts, links pivotally mounted 65 in pairs on the opposite ends thereof, spacers interposed between the links of each pair, wheels loosely mounted on the shafts intermediate and on the inside of the pairs of links in position to travel on the tracks, and plates 70 mounted upon and carried by the links.

3. In an apparatus of the character described, the combination with tracks, of a plurality of shafts, links pivotally mounted in pairs on the opposite ends thereof, a pair 75 of said links being mounted in spaced apart relation on each end of each of the shafts, spacers mounted on the shafts between the links of each pair for holding said links in spaced apart relation, and wheels mounted 80 on the shafts immediately adjacent the inside of the pairs of links at the opposite ends thereof in position to travel on the tracks.

4. In an apparatus of the character described, the combination with tracks and 85 chain wheels, of a plurality of shafts, links pivotally mounted in pairs on the opposite ends thereof, a pair of said links being mounted in spaced apart relation on each 90 end of each of the shafts, spacers mounted on the shafts between the links of each pair for holding said links in spaced apart relation, said spacers being arranged approximately in alignment with the chain wheels, and wheels mounted on the shafts immediately adjacent the inside of the pairs of links 95 at the opposite ends thereof in position to travel on the tracks.

5. In an apparatus of the character described, the combination with tracks and 100 chain wheels, of conveyer sprocket chains spaced apart from each other, each of said chains including a plurality of links arranged in pairs in spaced apart relation with each other, shafts connecting the chains 105 together and forming pivots for the links of said chains, spacers mounted on the shafts between the links of each pair for holding said links in spaced apart relation, said spacers being arranged approximately in 110

alignment with the chain wheels, and wheels mounted on the shafts immediately adjacent the inside of the pairs of links at the opposite ends thereof in position to travel on the tracks.

6. In an apparatus of the character described, the combination of a plurality of shafts, links pivotally mounted in pairs on the opposite ends thereof, a pair of said links

being mounted in spaced apart relation on each end of each of the shafts, spacers mounted on the shafts between the links of each pair for holding said links in spaced apart relation, and wheels mounted on the shafts immediately adjacent the inside of the pairs of links at the opposite ends thereof.

In testimony whereof I affix my signature.

SECONDO FREILINO.
